UNITED STATES PATENT OFFICE.

EVERETT M. DAVIS, OF CHICAGO, ILLINOIS, ASSIGNOR TO ADDIE J. DAVIS, OF MONSON, MASSACHUSETTS.

DESIGN FOR A BRACELET.

48,243.

Specification for Design.

Patented Dec. 7, 1915.

Application filed September 9, 1915. Serial No. 49,839. Term of patent 7 years.

To all whom it may concern:

Be it known that I, EVERETT M. DAVIS, a citizen of the United States, residing at Chicago, in the county of Cook and State of Illinois, have invented a new, original, and ornamental Design for Bracelets, of which the following is a specification, reference being had to the accompanying drawings, forming part thereof.

Figure 1 is a face view of a bracelet, showing my new design, and Fig. 2 is a corresponding plan view.

I claim:

The ornamental design for a bracelet, as shown.

EVERETT M. DAVIS.

Witnesses:

S. A. McNEVIN,
A. J. JOHNSON.
